(57) **CLAIM**

We claim the ornamental design for a liquid dispenser, as shown and described.

DESCRIPTION

FIG. 1 is a top view of a liquid dispenser showing the claimed design.

FIG. 2 is a side view of the liquid dispenser of FIG. 1. The opposing side view is a mirror image of FIG. 2.

FIG. 3 is a bottom view of the liquid dispenser of FIG. 1. FIG. 4 is a perspective view of the liquid dispenser of FIG. 1.

FIG. 5 is a front view of the liquid dispenser of FIG. 1; and, FIG. 6 is a rear view of the liquid dispenser of FIG. 1. The broken lines in the drawing views represent environmental structure and form no part of the claimed design.
